(57) **CLAIM**

The ornamental design for a burial urn containing a transparent material with laser-induced images, as shown and described.

DESCRIPTION

FIG. 1 is a front elevational view of a transparent material showing our new design;

FIG. 2 is a left elevational view thereof; the right side being a mirror image;

FIG. 3 is a top plan view thereof; and,

FIG. 4 is a bottom plan view thereof.
